UNITED STATES PATENT OFFICE

ROLLAND G. WILLIAMS, OF BRANFORD, CONNECTICUT, ASSIGNOR TO MALLEABLE IRON FITTINGS COMPANY, OF BRANFORD, CONNECTICUT, A CORPORATION OF CONNECTICUT

HIGHWAY GUARD FENCE FIXTURE

Application filed December 26, 1930. Serial No. 504,906.

This invention relates to a fixture for a highway guard fence, and has for its object to provide an economical device of this description which can be readily applied for use, and to which the usual fence cables in slack condition can be readily connected.

In the drawings

Figure 1 is a plan view illustrating the fixture applied to a fence post with the cable 10 in position.

Figure 2 is a section at the line 2—2 of Figure 1 looking in the direction of the right hand arrow, and

Figure 3 is a section at the coinciding line 15 3—3 of Figure 1 looking in the direction of the left hand arrow.

Similar numerals of reference denote like parts in the several figures of the drawings.

1 designates the posts, only one being 20 shown, and 2 generally designates the fixture which latter has an opening 3 extending through it from top to bottom and also has projecting from its forward end spaced hooks 4 and 5 which extends in opposite directions, 25 and from the rear of the fixture extend gripping spurs 6.

7 is a bolt which passes through the post, and has its forward portion formed into a hook 8 which latter extends through the 30 opening 3, the fixture being firmly secured to the post by means of a nut 9 applied to the threaded rear end of the bolt.

When this nut is tightened it will cause 35 the spurs 6 to dig into the post, and will thus draw the fixture tightly against the latter, as clearly shown in the drawings, the hooks 4 and 5 being spaced apart a distance greater than the width of the cable 10, and in applying the latter in its slackened condition it is 40 merely picked up and passed between the hooks so as to be positioned within the same, as clearly shown at Figure 1 and when the cable is tightened it will be impossible for it to become detached from these hooks.

45 What is claimed is

In a highway guard fence, a fixture for receiving fence cables having at one end reversely extending hooks that are spaced apart a distance greater than the width of 50 the fence cable whereby the latter in slackened

condition may be positioned within said hooks, and at the other end spaced flanges for engagement with a post and provided with a substantially centrally disposed aperture adapted to be engaged by means 55 for attaching said fixture to said post.

In testimony whereof I affix my signature hereto.

ROLLAND G. WILLIAMS.
